H. F. ROCKETT

MASSAGE APPARATUS

Filed Feb. 21, 1924

Patented Sept. 8, 1925.

1,552,507

UNITED STATES PATENT OFFICE.

HENRY F. ROCKETT, OF GASTONIA, NORTH CAROLINA.

MASSAGE APPARATUS.

Application filed February 21, 1924. Serial No. 694,296.

To all whom it may concern:

Be it known that I, HENRY F. ROCKETT, a citizen of the United States, residing at Gastonia, in the county of Gaston and State 5 of North Carolina, have invented certain new and useful Improvements in Massage Apparatus, of which the following is a specification.

This invention relates to massage apparatus, and particularly to apparatus of 10 this character especially adapted for treating the head and scalp.

The object of the invention is to provide a power driven device which will be simple 15 in construction, and efficient in operation, for thoroughly rubbing or massaging, at one time, a relatively large area of the head or scalp, such apparatus being designed to take the place of the usual hand manipulation, 20 as well as to supplant the small vibrators now in common use.

In order that the invention may be readily understood, reference is had to the accompanying drawing, forming part of this specification, and in which:—

Figure 1 is a rear face view of my improved apparatus;

Figure 2 is a vertical central section therethrough;

Figure 3 is a transverse section on the line 3—3 of Figure 2, looking in the direction of the arrow;

Figures 4 and 5 are fragmentary longitudinal sections, taken on planes at right 35 angles to each other, and illustrating a modified construction of the actuating mechanism; and

Figure 6 is a fragmentary sectional view on an enlarged scale, illustrating the method 40 of securing the rubbers to the supporting plate or base.

Referring to the drawing in detail, my improved device comprises a skeleton frame 1, preferably of elliptical shape, as clearly 45 shown in Figure 2, such frame being formed integral with or rigidly secured to a handle portion comprising a housing 2, and a handle proper, 3.

Within the elliptical skeleton frame 1 is 50 located a similarly shaped plate, back or base 4. This lies within the frame 1, and is arranged with its major axis co-inciding with, but somewhat shorter than that of the frame. The plate or back 4 is mounted to reciprocate within the frame by means of 55 pins 5, projecting outwardly from bosses 4^a,

formed on the plate. One such pin 5, which constitutes an extension of the major axis, works loosely in an opening 6 in the end of the frame 1, while two other pins 5 are disposed at the extremities of the minor axis and are received in slots 7, formed in the ring 1, such slots being covered by plates 7^a. 60

Projecting from the opposite end of the base or plate 4 is a pair of rods or bars 8, 65 both being rigidly secured to the plate or base and one of them being set into an up-standing boss 4^b thereon, as clearly shown in Figure 2. These bars 8 extend in spaced parallel relation into the housing 2, the open 70 opposite sides of which are closed by removable cover plates 2^a. Located within this housing between the bars 8, is a cam 9, having a peripheral cam slot 10 in its cylindrical surface, and in this slot works a pair 75 of pins 11, projecting inwardly from the bars 8. It will be understood, of course, that the bars 8 are mounted to reciprocate freely in the housing 2. The slot 10 is symmetrical, relative to the two pins 11. That is to 80 say, it contains two similar portions extending over 180° each.

The cam 9 is rigidly secured to a shaft 12, extending centrally through the housing and journaled in bearings 13 at suitable 85 points. This shaft also extends entirely through the hollow hand member 3, and is provided at its extreme end 14 with a suitable slot or socket adapted to receive one end of a flexible shaft, the extreme end of 90 the handle 3 being open, as indicated at 3^a, to permit the free passage of such shaft. This flexible shaft may be attached to and driven by an electric motor of the type usually employed to operate hair clippers, or the like. 95

The plate 4 is concave or saucer shaped, as clearly shown in Figure 2, and the concave face carries and is substantially covered by a series of rubbing elements 15. These rubbing elements are preferably in the nature 100 of knobs or fingers formed of soft india rubber or the like. They may be secured to the plate or back 4 by means of a screw 17, engaging a nut 16, embedded in the rubber. For the sake of simplicity, the 105 heads of these screws have not been illustrated in Figure 1.

From the foregoing, it will be understood that when the shaft 12 is rotated, as by means of the motor and flexible shaft referred to, the bars 8 and plate 4 will be reciprocated or vibrated. The operator then 110

grasps the handle 3 and applies the concave series of rubbers to the head of the person being treated, moving it slowly over the head, as may be required. The vibratory movement of the plate and rubbers produces a vigorous massaging action which is beneficial in inducing better circulation and is also useful in shampooing.

Instead of employing the pin and cam groove construction shown in Figures 1, 2 and 3, the plate or back 4 may be reciprocated or vibrated by other means. Thus, in Figures 4 and 5, I have shown a different mechanism for producing this vibration. Referring to these figures, instead of separate bars, I provide an H-shaped piece 8', having a cross bar 18, in which is formed a slot 19, and in this slot works a crank 20, secured at one end to a gear wheel 21, journaled in the housing 2', and driven by a pinion 23, carried by the shaft 22, extending through the handle 3. The other end of the crank 20 is supported by a stub shaft 24, also journaled in the housing 2'. Thus, it will be seen that as the pinion 23 revolves, the gear 21 and crank 20 are caused to rotate, thus reciprocating the H-shaped member 8' and vibrating the plate 4, which is rigidly attached thereto.

30 What I claim is:—

1. A massage device comprising a base plate, rubbing elements carried by one face thereof, a skeleton frame encircling said base plate, and within which said base plate is mounted to reciprocate; and means for reciprocating said plate in said frame.

2. A massage device comprising a base plate having a concave face, a series of rubbing elements carried by such concave face, a skeleton frame encircling said base plate, and within which said base plate is mounted to reciprocate, and means for reciprocating said plate in said frame. 40

3. A massage device comprising a skeleton frame, a handle portion rigid therewith, a plate fitting inside of said frame and mounted to reciprocate therein, rubbers carried by said plate, and mechanism within said handle portion for reciprocating said plate in the frame. 45 50

4. A massage device comprising an elliptical frame, a similarly shaped plate having a somewhat shorter major axis enclosed in and mounted to reciprocate within said frame, rubbing elements carried by said plate, and means for reciprocating said plate in the direction of its major axis. 55

5. A massage device comprising a base plate, rubbing elements carried by one face thereof, a skeleton frame encircling said base plate, one dimension of the inside of said frame being substantially equal to the width of said plate, and the other dimension being greater than the length of said plate, to provide a clearance whereby said plate may be reciprocated within said frame, means for so reciprocating said plate, and means for movably mounting the plate in said frame so as to prevent its separation but permit its reciprocation therein. 60 65 70

In testimony whereof I affix my signature.

HENRY F. ROCKETT.
